UNITED STATES PATENT OFFICE.

FELIX KIELINSKI, OF MILWAUKEE, WISCONSIN.

SCREW-DRIVER.

1,256,139.

Specification of Letters Patent. Patented Feb. 12, 1918.

Application filed April 18, 1917. Serial No. 163,251.

To all whom it may concern:

Be it known that I, FELIX KIELINSKI, a citizen of the United States, residing at Milwaukee, in the county of Milwaukee and 5 State of Wisconsin, have invented certain new and useful Improvements in Screw-Drivers, of which the following is a specification.

This invention relates to molders' tools 10 and has special reference to a draw screw holder.

It is a well known fact that in the process of molding, patterns are employed which are bedded in green sand, loam or the like, 15 the bedding material being usually held in what is known as a flask. After the pattern has been properly bedded it must then be withdrawn. Now, inasmuch as patterns are frequently bedded so that their upper surface is level with the sand the withdrawal 20 of the pattern, especially in two-part patterns where the upper surface is a plane, it becomes a matter of some difficulty. Under ordinary circumstances it is usual to 25 drive the tang of a file or the like into the pattern so that it may be lifted without disturbing, to any great extent, the molding material. However, this driving operation always results in some disturbance of the 30 molding material and in addition it frequently happens that the pattern is injured and that the tool can not be driven firmly enough to lift the pattern.

In order to obviate this I have invented 35 a simple tool for inserting a screw in a pattern, the screw being of the type usually employed with wood or being used in connection with a plate having a threaded opening and being in the form of a machine screw. This tool is also used as a 40 handle to lift the pattern.

One important object of the invention is 45 therefore to provide an improved and simplified tool adapted to insert a screw in a pattern and at the same time to act as a handle to lift the pattern out of the mold.

With the above and other objects in view, 50 as will be hereinafter apparent the invention consists in general of certain novel details of construction and combinations of parts hereinafter fully described, illustrated in the accompanying drawing, and specifically claimed.

In the accompanying drawing, like characters of reference indicate like parts in 55 the several views, and:—

Figure 1 is a side elevation of a tool constructed in accordance with this invention.

Fig. 2 is a vertical median section through such a tool the view being partly in elevation.

Fig. 3 is a section on the line 3—3 of Fig. 2.

Fig. 4 is a section on the line 4—4 of Fig. 2.

Fig. 5 is a detail perspective view of 65 one form of screw holder especially adapted for holding wood screws.

Fig. 6 is a modified form of screw holder especially adapted for holding machine 70 screws.

In the embodiment of the invention herein illustrated there has been shown a tool which comprises a body having a hollow cylindrical upper portion 10 which is threaded interiorly as at 11. The lower portion of this body is of inverted frusto-conical form and is provided with slots 12 wherethrough the fingers may be inserted for purposes hereinafter to be described. The 75 bottom end of the body is composed of a hollow cylindrical sleeve 13 threaded exteriorly.

Screwed into the upper portion 10 of said body is a sleeve 14 wherethrough extends a 85 boss 15 which forms the journal of a revolvable handle 16. Moreover, the boss 15 is of such length that a nut 17 may be screwed on its lower end and when so positioned may permit longitudinal movement of the 90 boss 15 through the sleeve 14. In the lower end of this boss 15 is a bit socket 17' whereto is fitted the polygonal end of a bit 18 which extends downward through the end 13, the bit being thus removable and its removal being effected by gripping the shank of the bit through the slots 12 with the fingers.

Screwed on the lower end of the body is a screw holder or support 19 which has at 100 one side an opening 20 below which is a seat 21 for the head of a screw 22. It will be noted that the form shown in Figs. 2 and 5 shows the seat 21 beveled so that the head of an ordinary wood screw may be received thereon while in the form shown in 105

Fig. 6 the seat is square to conform to the flat undersurface of the head of a machine screw.

In the operation of the device a suitable bit 18 is inserted in the bit socket and the handle 16 is raised. A screw is then slipped into the holder and the handle 16 depressed until the point of the bit 18 seats in the kerf of the screw 22. The point of the screw is then set on the pattern and the body gripped with the left hand while the right hand is used to rotate the handle 16 and thus force the screw into the pattern. After the screw is in position the handle 16 may be lifted which will result in the pattern also being lifted. Moreover, it will be noticed that the device may be readily detached from the screw after it has been inserted so that the screw may be lifted, if desired, in position in the pattern ready for the attachment of the device to lift the pattern.

There has thus been provided a simple and efficient device of the kind described and for the purpose specified.

It is obvious that many minor changes may be made in the form and construction

of the invention without departing from the material principles thereof. It is not therefore desired to confine the invention to the exact form herein shown and described but it is wished to include all such as properly come within the scope claimed.

Having thus described the invention, what is claimed as new, is:—

In a draw screw holder, a hollow body internally threaded at its upper end, a sleeve screwed into said upper end, a handle having a boss extending through said sleeve and rotatable therein, said boss being also movable longitudinally in the sleeve and provided at its lower end with a bit socket, a nut on the lower end of the boss limiting its longitudinal movement, a screw holder removably threaded on the lower end of the body, and a bit removably mounted in the socket and extending downward into the screw holder.

In testimony whereof I affix my signature.

FELIX KIETLINSKI.
